UNITED STATES PATENT OFFICE.

ROBERT G. CLARK, OF NEW YORK, N. Y.

CAN-BODY MACHINE.

1,182,645.

Specification of Letters Patent.

Patented May 9, 1916.

Application filed March 25, 1914. Serial No. 327,100.

To all whom it may concern:

Be it known that I, ROBERT G. CLARK, a citizen of the United States, and resident of the city of New York, borough of Brooklyn, county of Kings, and State of New York, have invented certain new and useful Improvements in a Can-Body Machine, of which the following is a specification.

This invention relates to a can body machine used in the manufacture of sheet metal can bodies.

The object of the invention is to provide a simplified and improved construction in a machine for forming can bodies in which the speed, output and efficiency of the machine are materially increased and, on account of an improved construction and arrangement of the parts, the cost of construction and operation of the machine is decreased.

Among the novel features of the invention is the mechanism for bending the metal blanks in a peculiar manner and the simultaneous operation upon the ends of the blank by a single tool or mechanism, all of which permits an extremely rapid operation and increased output of the machine.

The several consecutive operations upon the successive blanks are performed continuously and upon several blanks simultaneously, provision being made for advancing each blank from one operating station to another and simultaneously feeding forward another blank to take its place, consequently, no time is lost while the several successive operations are being performed upon any one blank.

Other novel features of the construction will appear more fully hereinafter in connection with the description of the machine embodying the invention as illustrated in the accompanying drawings, the operation of which will be fully described hereinafter and the novel features defined in the claims.

In the drawings like parts in the several views have been given the same reference numerals.

Figure 1 is a side elevation of a can body machine. Fig. 2 is an enlarged plan view, partly in section, of the central portion of the machine shown in Fig. 1. Fig. 3 is an enlarged sectional view on the line 3—3 of Fig. 1. Fig. 4 is an enlarged sectional view on the line 4—4 of Fig. 1. Fig. 4^a is a detail

longitudinal vertical section on a line passing through the forming horn, showing in face view the notching cutters illustrated in Fig. 4. Fig. 5 is an enlarged sectional view on the line 5—5 of Fig. 1. Fig. 6 is a perspective view of a portion of the mechanism shown in Fig. 5. Fig. 7 is an enlarged sectional view on the line 7—7 of Fig. 1. Fig. 8 is a sectional side elevation of a portion of the mechanism shown in Fig. 7, taken on the line 8—8. Fig. 9 is an enlarged sectional view on the line 9—9 of Fig. 1. Fig. 10 is an enlarged sectional view of a portion of the machine shown in Fig. 1, taken on the line 10—10. Fig. 11 is an enlarged sectional view of a portion of the machine shown in Fig. 1, taken on the line 11—11. Fig. 12 is an enlarged sectional view taken on the line 12—12 of Fig. 1. Fig. 13 is a view of a portion of Fig. 12, showing a subsequent position of the mechanism. Fig. 14 is a sectional view taken on the line 14—14 of Fig. 12. Figs. 15, 16 and 17 are fragmentary views showing consecutive operations of the mechanism shown in Figs. 12, 13 and 14. Fig. 18 is an enlarged fragmentary sectional view of a portion of the feeding mechanism, taken on the line 18—18 of Fig. 2. Fig. 19 is a fragmentary top plan view of a portion of one of the feed bars. Fig. 20 is a sectional view on the line 20—20 of Fig. 19. Fig. 21 is a sectional view on the line 21—21 of Fig. 19.

A suitable base 1 is provided with an upright 2 and an upright bumper column 3 which support the table 4 upon which a reciprocating slide 5 is mounted. A cross head 6 is attached to and operates the reciprocating slide 5, the cross head being operated from a crank disk 7 mounted upon a shaft 8 which is driven by any suitable means, such as the driving pulley 9.

The means for operating the reciprocating slide 5 from the cross head 6 comprise a crank block 10 and a crank pin 11 on the crank disk 7. The crank block 10 is received in a vertical slot in the cross head 6, which is also provided with a horizontal slot through which the shaft 8 passes, thus causing a reciprocating movement to be imparted to the cross head 6 and slide 5 as the crank disk 7 is rotated, as will be understood by reference to Figs. 1 and 12.

A feed bar support 12 is mounted upon

the reciprocating slide 5, to which the feed bars 29, 30 and 31 are adjustably attached at their ends. The feed dogs 14 are pivotally attached to the support 12 at 15 and 5 normally held in their operative position by means of the spring 16.

The metal blanks from which the can bodies are to be formed are placed in the support 17 one at a time in the position, 10 shown at A in Fig. 1. The successive positions of the blank, or successive blanks, as the same are fed through the machine and operated upon, is indicated in the several views by A, B, C, D, E, F, G and H.

15 An automatic device for placing the blanks successively in position in the support 17 may be used in connection with this machine, if desired, but for the purposes of this application the machine is shown in a 20 simple form in which the blanks are placed in position by hand in the support 17.

As the upper feed bar 31 is moved forward with the slide 5 the feed dogs 14 engage the blank and move the same from its 25 position at A to the position indicated at B, where it passes under the forming wings 18 and 19, as shown in Fig. 3. The forming wings are pivotally mounted upon the table 4 at 20-20', and 21-21', respectively, and 30 are locked in their closed position by means of the locking handles 22 and 22' (for the forming wing 18) and 23 and 23' (for the forming wing 19). The locking handles 22 and 22' are each provided with a lip 24 at 35 the lower end and the locking handles 23 and 23' with a similar lip 25 (Fig. 3). When the locking handles are swung to their closed positions these lips 24 and 25 engage beneath corresponding projections 40 from the table 4 and thus the forming wings 18 and 19 are locked in their closed or operative positions. This construction provides easy means of access to the blanks in the machine, to remove the same if they 45 become jammed and also for access to the interior of the machine, by merely unlocking the handles and swinging the forming wings about their pivots.

The wings 18 and 19 are shaped at their 50 forward ends to provide outer members for forming or bending the blank about the horn the rear portion of the wings constituting guides for holding the blank as the same is advanced and operated upon, as will be explained hereinafter. The forming ends of the wings may be separate therefrom if desired.

The blanks are now advanced from the position shown at B to that shown at C in 55 Figs. 1 and 3 by means of the reciprocating top feed bar 31, which is provided with a dog 32 arranged to engage the same, this feed bar and dog being shown in detail in Fig. 18. The dog 32 is positioned in a slot

in the top feed bar 31 and is normally held 65 in its operative position by means of a spring, which permits the same to pass under the blank when the feed bar is moved to the left, the blank being held against return movement by spring operated latch 70 members 13 and 13' mounted in the wings 18 and 19, respectively.

In its forward movement the blank is bent downwardly on either side by the curved faces on the forward ends of the 75 wings 18 and 19 over the forming horn 26 into an inverted U shape and the lower ends of the blank are engaged by guide shoes 27 and 28, which cause the blank to be evenly positioned upon the forming horn.

80 The blank is now engaged by the reciprocating side feed bars 29 and 30 and advanced from position C to position D, Figs. 1 and 4. The side feed bars are shown in detail in Figs. 19, 20 and 21 and are provided with a number of dogs, such as 33, positioned in transverse slots and are held in position to engage the blanks by means of the spring 34, which is engaged in longitudinal slots in the feed bar and dog, the 90 opposite end of the dog forming a pivot and abutting against the end of the slot, as shown. The spring 34 abuts against one end of the slot in the dog 33, thus holding the same in position. This provides a 95 simple construction in which the dogs may be readily placed in position or removed by forcing the spring 34 out of its slot in the feed bar and sliding the dog and spring sidewise out of the feed bar. As the feed 100 bar is reciprocated the projecting end of the dog is forced downwardly and passes under the blank and then springs up to engage the same on its return, as will be readily understood.

105 The blanks are now advanced by the side feed bars 29 and 30 into the position indicated at D in Fig. 4, in which position the operation of notching the corners of the blank is performed. A notching die 35 is 110 mounted in the wing 19 and a similar notching die 36 is mounted in the horn 26, as shown. Two pairs of notching cutters 37-37' and 38-38' are adjustably mounted upon the notching block 39 by means of the bolts 115 40 and 41 for the notching cutter 37, the bolts 42 and 43 for the notching cutter 38, the bolts 40' and 41' for the notching cutter 37', and the bolts 42' and 43' for the notching cutter 38'. The cutters of the 120 respective pairs are located one behind the other, as shown in Fig. 4. The cutters of the respective pairs are located one behind the other as shown in Fig. 4. The notching block 39 is mounted upon a support 44, 125 which is movable transversely on the table 4, as will be described hereinafter. The transverse movement of the support 44

causes the notching cutters 37, 37' and 38, 38' to cut the notches simultaneously in the downwardly projecting ends of the blank D these notches being indicated at *d*, 5 Fig. 4^a.

The blank is next advanced into the position indicated at E in Fig. 5, where the operation of bending the ends preliminary to forming the hooks is performed. A bending die 45 is mounted in the horn 26 and a second bending die 46 is similarly mounted in the wing 19. Bending tools 47 and 48 are adjustably mounted upon the block 49, which is attached to the support 44. A block 50 is attached to the bottom of the support 44 and is received in an angular slot in the reciprocating slide 5, as shown in Figs. 5 and 6. The reciprocating movement of the slide 5 causes a transverse movement of the support 44, together with the notching cutters shown and described in connection with Fig. 4 and the bending tools shown in Fig. 5, just described. The bending operation is thus performed simultaneously upon the 25 two lower ends of the blank.

The blank is next advanced into the position F shown in Fig. 7, in which position the ends thereof are acted upon by a second bending device to form the hooks. A hook forming die 51 is positioned in the horn 26 and a similar die 52 is positioned in the wing 19. A forming block 53 is mounted on the lower side of the wing 18 and a similar block 54 is mounted on the lower side 35 of the horn 26. Hook forming tools 55 and 56 are adjustably mounted upon the support 57 which is, in turn, mounted upon the block 58. A cam block 59 is attached to the slide 5, as shown in Figs. 7 and 8, 40 and, as the slide 5 is reciprocated, causes the support 58 and the hook forming tools carried thereby to be raised and lowered, engaging the bent ends of the blank and thus forming the hooks upon the two lower 45 ends of the blank simultaneously. Support 58 is held against longitudinal movement on the bed-plate 4, by one of the guides for the slide 44 and the supporting block for the folder blades 60 and 61, as will be seen 50 from Fig. 1.

The blank is next advanced into the position shown at G in Fig. 9, where the two lower ends are engaged by the converging edges of the folder blades 60 and 61 which 55 bring the hooks on the lower edges thereof together, as the blank is advanced into the position shown at H in Figs. 10 and 11.

The next and final operation is the closing of the hooks to form the joint on the side 60 of the can body. The mechanism for performing this operation is shown in Figs. 12, 13 and 14. A bumper anvil 62 is mounted upon the bumper column 3. A safety spring 63 is positioned between the upper side of

the bumper anvil 62 and adjusting screws 65 in the bumper column 3. The purpose of the safety spring is to provide a slight yielding and adjustment of the anvil to prevent the breaking of the mechanism and frame if the can bodies become jammed, etc. The 70 bumper 64 is slidably mounted in the frame and is engaged by a cam 65 attached to the crank disk 7, as shown in Figs. 12 and 13. A facing block 66 of hardened steel is attached to the lower side of the bumper 64 75 and is engaged by the cam 65, which raises the bumper, causing the same to be moved to the right as the facing 66 engages the fixed cam face 67 and then upwardly to the position shown in Fig. 13. An upper cam 80 face 68 is adjustably mounted on the frame and is engaged by the cam shoe 69 on the bumper 64 as the same is moved as just described. This causes the bumper and its attached parts to move bodily to the right 85 and then upwardly in a parallelism or without changing its angular position against the spring 70, which returns the same to its lower position as the cam 65 rotates, these movements being shown in Figs 12 90 and 13.

While the movement of the cam 64 just described is being performed the vertical bumper steel 72 is caused to engage the hook ends of the blank, pressing the same together and the upward movement causes the flat bumper steel 71 to engage the joined hooks and close the seam by forcing the same into the slot in the bumper steel 73 in the horn 26. The vertical bumper steel 72 95 is supported upon a spring and yields downwardly as this last operation is performed, as shown in Fig. 13. These successive operations of forming the joint or seam are shown in Figs. 15, 16 and 17. The can body 100 thus formed is then delivered from the horn 26.

It will thus be seen that a novel arrangement and sequence of the several operations is provided. First bending the blank into 110 U shape and then performing successively the several operations of notching, hook forming, engaging the hooks and closing the seam on the two lower ends simultaneously. A very simple construction is provided for 115 performing these operations and the number of operating parts is considerably reduced, thus simplifying the construction of the machine as a whole. This permits very rapid operation of the machine and results in a 120 substantial increase in the output and efficiency.

As many changes could be made in the above construction and many apparently 125 widely different embodiments of my invention designed without departing from the scope of the appended claims, I intend that all matter contained in the above description

or shown in the accompanying drawings shall be interpreted as illustrative merely of an operative embodiment of my invention and not in a limiting sense.

5. What I claim is:—

1. The combination in a can body machine, of means adapted to operate successively in the order named for bending, notching, forming the hooks, engaging the 10 hooks and closing the seam of the blank, and means for advancing the blank for said successive operations thereupon.

2. The combination in a can body machine, of means adapted to operate successively in the order named for bending the 15 blank into a U shape, notching, forming the hooks, engaging the hooks and closing the seam of the blank, and means for advancing the blank for said successive operations thereupon.

3. The combination in a can body machine, of means adapted to operate successively in the order named for bending the blank into an inverted U shape, notching, 25 forming the hooks, engaging the hooks and closing the seam of the blank, and means for advancing the blank for said successive operations thereupon.

4. The combination in a can body machine, of means for bending the blank into a U shape, means adapted to operate upon the ends of the blank after the latter has been bent into a U shape to adapt said ends to interlock, guides adapted to hold the blank 35 in position while being operated upon, said guides being removable from their operative position, means for securing and holding said guides stationary in their operative position, and means for advancing the blank.

40 5. The combination in a can body machine, of means for bending the blank into a U shape, means adapted to form hoops upon the ends of the blank after the latter has been bent to U shape, stationary folders positioned and adapted to engage the said ends 45 of the blank and bend the same inwardly into engagement with each other, means for joining said ends, and means for advancing the blank for said successive operations 50 thereupon.

6. The combination in a can body machine, of notching mechanism comprising a pair of cutting devices located one behind the other and adapted to operate upon opposite ends of a can body blank, means adapted to impart a reciprocating rectilinear movement to said cutting devices, means for holding the blank in position to be operated upon by said cutting devices, and means for 55 feeding the blanks successively thereto.

60 7. The combination in a can body machine, of notching mechanism comprising a pair of cutters, located one behind the other and adapted to operate upon opposite ends

of a can body blank, means adapted to impart a reciprocating rectilinear movement to said cutters, means for holding the blank in position to be operated upon by said cutters, and means for feeding the blanks successively thereto.

70 8. The combination in a can body machine, of notching mechanism comprising a cutting device consisting of a pair of cutters mounted one behind the other on a common support and adapted to operate upon opposite ends of a can body blank, means adapted to impart a reciprocating rectilinear movement to said cutting device, means for holding the blank in position to be operated upon by said cutting device, and means for feeding the blanks successively thereto.

85 9. The combination in a can body machine, of means for forming the blank into a U shape, notching mechanism comprising a cutting device adapted to act upon the ends of said U shaped blank, means adapted to impart a reciprocating rectilinear movement to said cutting device, means for holding the blank in position to be operated 90 upon by said cutting device, and means for feeding the blanks successively thereto.

95 10. The combination in a can body machine, of means for forming the blank into a U shape, a cutting device adapted to act upon the ends of said U shaped blank, means for operating said cutting device, means for holding the blank in position to be operated upon by said cutting device, and means for feeding the blanks successively thereto.

100 11. The combination in a can body machine, of means for forming the blank into a U shape, a cutting device adapted to notch the ends of said U shaped blank, means for operating said cutting device, means for holding the projecting ends of the blank in position to be operated upon by said cutting device, and means for feeding the blanks successively thereto.

110 12. The combination in a can body machine, of means for forming the blank into an inverted U shape, notching mechanism comprising a cutting device adapted to notch the ends of said U shaped blank, means adapted to impart a reciprocating rectilinear movement to said cutting device, means for holding the blank in position to be operated upon by said cutting device, and means for feeding the blanks successively thereto.

120 13. The combination in a can body machine, of means for forming the blank into a U shape, hook forming mechanism comprising, an initial bending device having a pair of bending tools located one behind the other and adapted to operate upon opposite ends of said U shaped blank, means adapted to impart a reciprocating recti-

linear movement to said initial bending device, a second bending device having a pair of bending tools located one behind the other and adapted to operate upon opposite 5 ends of said U shaped blank, means for imparting a reciprocating rectilinear movement to said second bending device, means for holding the blank in position to be operated upon by said devices, and means for feeding the blanks successively thereto.

14. The combination in a can body machine, of hook forming mechanism comprising, an initial pair of bending tools mounted upon a common support, means for imparting a reciprocating rectilinear movement thereto, a second pair of hook bending tools mounted upon a common support, means for imparting a reciprocating rectilinear movement thereto, means for holding the blank in position to be operated upon by said tools, and means for feeding the blanks successively thereto.

15. The combination in a can body machine, of means for forming the blank into an inverted U shape, hook forming mechanism comprising, an initial pair of bending tools mounted upon a common support, means for imparting a reciprocating rectilinear movement thereto, a second pair of bending tools mounted upon a common support, means for imparting a reciprocating rectilinear movement thereto, means for holding the blank in position to be operated upon by said tools, and means for feeding the blanks successively thereto.

16. The combination in a can body machine, of hook forming mechanism comprising, an initial pair of bending tools mounted upon a common support, means for imparting a horizontal reciprocating rectilinear movement thereto, a second pair of bending tools mounted upon a common support, means for imparting a vertical reciprocating rectilinear movement thereto, means for holding the blank in position to be operated upon by said tools, and means for feeding the blanks successively thereto.

17. The combination in a can body machine, of means for forming the blank into a U shape, a cutting device for notching the ends of the blank, an initial bending device for bending the ends of the blank, a common support upon which said cutting device and bending device are mounted, means for imparting a reciprocating rectilinear movement to said support, a second bending device adapted to bend the ends of the blank into hook form, means for operating said device, means for holding the blank, and means for feeding the blanks successively thereto.

18. The combination in a can body machine, of means for forming the blank, means for engaging the ends thereof, a bumper pro-

vided with a portion for closing the engaged ends of the blank and a portion for closing the seam, and means for imparting movement to said bumper bodily sidewise and upward without change of angular position to form the seam.

19. The combination in a can body machine, of means for forming the blank into an inverted U shape, means for engaging the ends thereof, a bumper provided with a portion for closing the engaged ends of the blank and a portion for closing the seam, and means for imparting movement to said bumper bodily sidewise and upward without change of angular position to form the seam.

20. The combination in a can body machine, of means for forming the blank, means for engaging the ends thereof, a bumper provided with a portion for closing the engaged ends of the blank and a portion for closing the seam, and a series of cams adapted to impart movement to said bumper bodily sidewise and upward without change of angular position to form the seam.

21. The combination in a can body machine, of means for forming the blank into a U shape, a removable guide for the blanks, a notching die positioned in said guide, a notching cutter, means for operating said cutter, and means for feeding the blanks.

22. The combination in a can body machine, of means for forming the blank into a U shape, a removable guide for the blanks, a bending die positioned in said guide, a bending tool, means for operating said tool, and means for feeding the blanks.

23. The combination in a can body machine, of means for forming the blank into a U shape, a removable guide for the blanks, hook forming dies positioned in said guide, hook forming tools, means for operating said tools, and means for feeding the blanks.

24. The combination in a can body machine, of blank feeding means including a reciprocating slide, a notching device, a bending device, and means whereby said slide is caused to operate the said notching and bending devices.

25. The combination in a can body machine, of means for forming the blank, means for engaging the ends thereof, a bumper provided with a portion for closing the engaged ends of the blank and a portion for closing the seam, means for moving said bumper toward the blank, and cooperating cam devices formed on the upper and lower ends of the bumper and on adjacent portions of the machine whereby said bumper is caused to move sidewise when operated by the said means.

26. The combination in a can body machine, of means for forming the blank, means for engaging the ends thereof, a bumper provided with a portion for closing the

engaged end of the blank and a portion for closing the seam, the first mentioned portion being yieldingly mounted in the bumper, and means for imparting movement to 5 said bumper bodily sidewise and upward without change of angular position to form the seam, the first mentioned portion being operated by the sidewise movement of the bumper and being adapted to yield to allow

of upward movement of the seam closing 10 portion.

Signed at the city, county and State of New York, this 24th day of March, 1914.

ROBERT G. CLARK.
